Term of patent 14 years

(Cl. D48—20)

Fig 3

FIG. 1 is a perspective view of a floodlight housing or similar article showing my new design.

FIG. 2 is a reduced rear elevational view of FIG. 1.

FIG. 3 is a reduced side elevational view of FIG. 1.

FIG. 4 is a reduced fragmentary front elevational view of FIG. 1.

The dominant features of my design reside in the portions shown in full lines.

I claim:

The ornamental design for a floodlight housing or similar article, substantially as shown and described.
